UNITED STATES PATENT OFFICE

168,534

COMBINED WEDGE AND SPUR FOR LOGGING OPERATIONS OR THE LIKE

John M. Council, Wananish, N. C.

Application March 14, 1952, Serial No. 18,910

Term of patent 3½ years

(Cl. D93—4)

To all whom it may concern:

Be it known that I, John M. Council, a citizen of the United States, residing at Wananish, in the State of North Carolina, have invented a new, original, and ornamental Design for a Combined Wedge and Spur for Logging Operations or the like, of which the following is a specification, reference being had to the accompanying drawing, forming a part thereof.

Figure 1 is a perspective view of a combined wedge and spur for logging operations or the like embodying my new design;

Figure 2 is a side elevational view;

Figure 3 is a front elevational view;

Figure 4 is a rear elevational view, and

Figure 5 is a bottom plan view.

I claim:

The ornamental design for a combined wedge and spur for logging operations or the like, as shown.

JOHN M. COUNCIL.
